UNITED STATES PATENT OFFICE.

RANDOLPH CROMPTON, OF WORCESTER, MASSACHUSETTS.

TRAVELER RING AND TRAVELER FOR SPINNING OR TWISTER FRAMES.

Application filed November 19, 1921. Serial No. 516,457.

This invention relates to traveler rings and travelers and particularly to stationarily mounted rings and travelers therefor for spinning and twister frames.

In order that the principle of the invention may be readily understood, I have represented a single embodiment thereof in the accompanying drawing, wherein,—

Fig. 1 is a side elevation of a ring and 10 the support therefor;

Fig. 2 is a vertical central section of the construction shown in Fig. 1 upon the line 2—2 of said figure; and

Fig. 3 is a side elevation similar to Fig. 15 1 but representing the ring as detached from its support or holder.

An important object of my invention is to provide a ring having certain properties including that of self-lubrication, the ring 20 being preferably also non-corrosive and non-oxidizable and of superhardness and capable of sustaining the spinning or twisting operation for a maximum length of time without wear. In the preferred and 25 disclosed embodiment of the invention the ring is reversible in actual practice and even after a long period of use and particularly because of the fact that the ring is non-corrosive and non-oxidizable. These and 30 other important features of the invention will be more fully disclosed.

Referring more particularly to the drawing, the ring holder or support is indicated at 1, it being of any suitable material and 35 construction not herein necessary more fully to disclose. Preferably said holder or support is formed as a split ring or body as indicated at 2, so that it may frictionally engage and hold from rotation the ring indicated generally at 3. If desired and as 40 shown a clearer 4 of any suitable construction may be employed, it being here shown as a wire coiled to lie in the groove 5 in the top face of the support or holder 1 with an 45 upwardly extending inclined end as illustrated. The said holder or support is provided with an upstanding flange providing a shoulder 6 for the reception at its inner side of the ring 3.

The ring 3 may be of any suitable form 50 but desirably it is reversible. To that end it is provided as herein represented with flanges 7 and 8 at opposite ends thereof, either flange being capable of being received and held by the support or holder 1. If desired, any suitable cooperating means

may be provided to retain the ring fixedly within the support or holder, as, for example, retaining clips or other suitable parts or devices. The invention is not limited to 60 a ring held from rotation but the disclosed and preferable embodiment of the invention is a ring which is fixed during the operation.

The ring is provided with a suitable 65 traveler 9 which may be of any suitable shape and is received over the upper flange. Within the scope and purpose of my invention the traveler may be of any suitable and usual material such as steel or it may be 70 of some material such as that herein disclosed with respect to the ring 3, as will be more fully set forth.

Rings as now generally made are cut from a tube of steel and are thereafter ground. 75 and in some cases rings have been spun, or forged or stamped from sheet metal and subsequently welded. Such rings are of very uncertain length of life, lasting in some cases about six months and in other 80 cases as much as five years or more.

It has heretofore been proposed to make a ring reversible and in fact a usual construction of ring is one having top and bottom flanges for the purpose of permitting 85 reversal thereof. As a matter of fact, however, an acceptable and successfully reversible ring has never been produced so far as I am aware because if one end of the ring 90 be used for the traveler for a few months or even longer, as, for example, the flange 7, and it then is desired to reverse the ring and use the flange 8 for the traveler, it is found that the flange 8 has oxidized or 95 become corroded to such an extent as to render it no longer practicable to reverse the ring and use the said flange 8 for the traveler. Hence, a ring that is really and in fact reversible has not been heretofore produced so far as I am aware.

Owing to the high speed at which a traveler rotates about the ring, such speed averaging between 1500 and 12000 revolutions per minute, it is of the highest importance that the ring be of a material that is hard 100 and will withstand wear. Heretofore so far as I am aware, however, no material has been found to be satisfactory, in that after a greater or less length of time the ring wears to such an extent that it must be discarded. 105 It has not been feasible heretofore to lubricate a traveler ring or the traveler in general

operation thereof because oil and grease must obviously be kept away from the commercial yarn that is being spun.

After a great deal of experimentation I have produced a ring that is not only non-corrosive and non-oxidizable, thereby permitting it to be actually reversed, but its high degree of hardness combined with its self-lubricating properties permits it to be 10 used for a greater length of time than has heretofore been possible.

My invention comprehends a ring composed of a metal or a metallic alloy which in and of itself is a lubricant, and which is desirably non-corrosive and non-oxidizable, but preferably and to secure the results herein specified, the ring is composed at least in 15 part of chromium and desirably is composed of chromium and cobalt or nickel and preferably in the proportions of somewhat more 20 than ten per cent, and somewhat less than about fifty per cent. of chromium, at least a part of the remainder of the alloy being cobalt, or it may be nickel. Other metallic ingredients may be included but for the purposes of the present disclosure the ring may 25 be regarded as made at least mainly of chromium, and cobalt or nickel.

I may construct the ring of my invention 30 in any suitable way, and I make reference to three methods of manufacture, two of which methods will result in a solid ring of the alloy above outlined; the third method produces a ring of steel coated or surfaced 35 with the alloy above outlined. In my preferable method I cast in the rough a ring out of the suitable alloy, then grind the ring both on the inside and the outside and on both flanges, lastly, I polish the ring until it presents 40 an absolutely smooth surface. In my second method, I roll into shape a ring of the desired form after which it is necessary only to polish the ring. The rolling into shape is done hot, and it is possible to work 45 the above outlined alloy when to the elements already mentioned is added a slight quantity of iron, not more than twenty per cent.

The third method consists in making an 50 under size ring of steel by any well known method, placing this ring on a rapidly rotating spindle and spraying thereupon the alloy outlined by means of an electric arc of oxy-hydrogen, or oxy-acetylene element 55 which fuses any desired metal or material, combined with an air stream preferably of about three atmospheres pressure which atomizes the fused material and projects it upon any desired surface. Such spraying 60 machine may be and desirably is, of the type invented by one M. U. Schoop, of Zurich, Switzerland, and disclosed in United States Patent No. 1,133,507, dated March 30, 1915.

Such a ring is extremely hard and may be 65 defined as superhard. It is capable of re-

ceiving and sustaining a very high polish. It is inherently self-lubricating and therefore for the first time in the art, so far as I am aware, there is thus produced a ring that is in substance self-lubricating and rendered 70 so without the employment of any material treated with an oil or other lubricant. By this I do not mean that the substance of the alloy yields an oil or grease but that the ingredients of the alloy so co-act upon or with 75 the traveler as to lubricate the rubbing surfaces of these parts and lessen their friction upon each other.

Because of the fact that the ring is of great or super-hardness, it is possible to run 80 the traveler at a higher speed than heretofore customary.

I have stated that the traveler 9 may be made of any suitable material. The length of life of a traveler is exceedingly uncertain. It frequently lasts but a few minutes or hours and again it may run for some days or even weeks under certain conditions. It is therefore desirable to provide a traveler for some material that will last longer than 90 heretofore and be of more certain life. Therefore, desirably I make the traveler of substantially the same metal or alloy as the ring, namely, of chromium with cobalt or nickel. In doing so I provide for the first 95 time in the art a metallic traveler which is itself self-lubricating and which does not corrode or oxidize. Such traveler may be made in any suitable way.

It is not essential to my invention that the 100 entire traveler ring be made of a material having the qualities or certain of the qualities mentioned, although this is preferable. Within the scope of my invention one or both of the flanges 7 and 8 or the upstanding 105 portion 10 of the ring may be of such material. It is not, of course, essential that the ring 3 be absolutely fixed in operation as it may or can turn more or less and even though not desirable, within the broad scope 110 and purpose of my invention it may be of the so-called rotary type of ring.

I have set forth that the ring of my invention is non-corrosive or non-oxidizable. I have also set forth that it is of great hardness. These two qualities combine to produce a highly efficient ring. It is well known that certain materials, such as aluminum, are non-corrosive, but they would 115 be wholly unsuitable for use as a spinning 120 or twister ring because they are relatively soft.

It has heretofore been proposed to provide a ring with a lining or wood treated with some lubricating material to reduce friction. Such material, however, wears very rapidly and obviously does not possess many of the properties of the material preferably employed by me.

It has also heretofore been proposed to 125

construct a ring of ceramic materials, including earthenware and porcelain, and also to construct it of glass. These materials have in practice been found to be unsuited for the purpose, being relatively fragile and breaking easily and short lived. Moreover in the case of glazed material, it has been found that after a comparatively short time the glazed surface wears away and the underneath material is wholly unusable as a spinning or twister ring surface.

Moreover, excepting where some such material as wood is treated with a lubricant, there is no feature or characteristic of lubrication involved.

In those cases where a material such as wood is employed, and is saturated or treated with a lubricating material, it is obvious that not only is the lubricant-receiving material soft, but it is of an open, porous nature that is essentially different from the nature of the material employed by me.

I am aware that heretofore rings of metal have been actually lubricated with oil or other lubricating material, conducted thereto by capillarity or otherwise. Such provision, however, is seriously objectionable because it brings the oil or other lubricant into actual contact with the fibres that are being spun, to the great detriment thereof.

It has also been proposed to construct a ring traveler of some non-metallic material, such as horn, hard india rubber or rawhide, but so far as I am aware, such a traveler has never been used to any substantial extent, since it is obvious that such a traveler must be of short durability or life.

Having thus described one illustrative embodiment of my invention, I desire it to be understood that although specific terms are employed, they are used in a generic and descriptive sense and not for purposes of limitation, the scope of the invention being set forth in the following claims.

Claims—

1. A metallic traveler ring for textile purposes formed of an alloy of inherent superhardness and having inherent non-corrosive and anti-frictional properties

whereby said ring when polished and without artificial hardening or tempering operates with a minimum of friction.

2. A metallic traveler ring for textile purposes formed of an alloy of inherent superhardness and having inherent non-corrosive properties and which, without artificial hardening or tempering, when polished operates with a minimum of friction.

3. A metallic traveler for textile purposes formed of an alloy of inherent superhardness and having inherent non-corrosive and anti-frictional properties whereby said traveler when polished and without artificial hardening or tempering operates with a minimum of friction.

4. A metallic traveler for textile purposes formed of an alloy of inherent superhardness and having inherent non-corrosive properties and which, without artificial hardening or tempering, when polished operates with a minimum of friction.

5. A metallic traveler ring having a traveler flange at each end, composed of a superhard non-oxidizable and non-corrosive material, thereby rendering the ring acceptably reversible after a prolonged period of use of one of the said flanges as a running surface for the traveler, said ring having inherent anti-frictional properties.

6. A metallic traveler ring composed of an alloy containing chromium to a substantial extent, thereby rendering the ring superhard and inherently anti-frictional, said ring having at each end a traveler flange containing chromium, whereby said flanges are non-oxidizable and non-corrosive, thereby rendering the ring acceptably reversible after a prolonged period of use of one of the said flanges as a running surface for the traveler.

7. A metallic traveler for textile purposes having a superhard surface that is non-oxidizable and non-corrosive and which has inherent anti-frictional properties.

In testimony whereof, I have signed my name to this specification.

RANDOLPH CROMPTON.
